EMIL HAEFELY, OF BASEL, SWITZERLAND, ASSIGNOR TO WESTINGHOUSE ELECTRIC
AND MANUFACTURING COMPANY, A CORPORATION OF PENNSYLVANIA.

FORMING-PRESS.

1,028,108.

Specification of Letters Patent. Patented June 4, 1912.

Application filed July 10, 1909. Serial No. 507,001.

To all whom it may concern:

Be it known that I, EMIL HAEFELY, a citizen of the Republic of Switzerland, and a resident of Basel, in Switzerland, have 5 invented a new and useful Improvement in Forming-Presses, of which the following is a specification.

My invention relates to forming presses, and it has for its object to provide a device 10 of this character that shall be specially adapted for shaping or forming insulating tubes of rectangular cross section.

It is frequently desirable to produce insulating tubes of square or rectangular cross 15 section for use with electrical apparatus, and tubes of this sort are ordinarily produced by reheating a tube of circular cross section and forming it into the desired shape.

According to my present invention, I provide 20 a forming press which is simple and durable in construction and which produces a substantially uniform pressure on all sides of a square or rectangular object, so that it is particularly well adapted for the forming 25 process above referred to.

Figure 1 of the accompanying drawings is a partially sectional elevation of a forming press constructed in accordance with my invention, and Fig. 2 is an elevation at right 30 angles to that of Fig. 1.

Referring to the drawings, the structure here shown comprises a body member 1 which may be supported from any suitable base 1^a, a bed plate 2 secured to the body member, and a bracket arm 3 which is integral therewith and extends upwardly therefrom.

A pair of angle plates 4 and 5 are disposed 40 on the bed plate 2 in substantially parallel planes and a pressure member 6 having a plane bottom surface 7 is suspended from a feed screw 8 which is substantially vertical and is threaded through a hub 9 upon the end of the bracket 3. A hand wheel 10 is secured to the upper end of the feed screw 8, and a rotatable connection is established between the lower end of the feed screw and the pressure member so that the latter may be raised and lowered without being turned 45 on its axis as the hand wheel is rotated. The angle plates 4 and 5 and pressure members 50 6 are equal in length and their actual length will be determined by the nature of the work for which the press is intended.

55 The angle plates are similar to each other

and each is provided with a lateral projection 11 which extends throughout its whole length and produces a shoulder on its vertical pressure surface. A bar 12, which is slightly less in width than the thickness of 60 the article to be formed, rests on the shoulders provided by the projections 11 and is adapted to have the work laid upon it before the pressure is applied. The angle plates 4 and 5 may be adjusted laterally, by 65 means of screws 13, which are threaded through projections 14 on the bed plate 2, and engage cup-shaped recesses 15 in the outer edges of the said angle plates.

The adjacent edges of the angle plates 70 are raised slightly from the bed plate 2, by means of spring-supported rods 16, except when the pressure member 6 is forced into engagement with the upper surface of a tube 17, which is intended to be illustrative of any suitable object in process of formation on the press. Each of the rods 16 is provided with a head or engagement 75 16^a which is adapted to lie in a recess 2^a in the bed plate 2, through which the rod 80 16 projects except when the downward pressure of the member 6 is withdrawn. A spring 19, which is coiled about the shank 18 of the rod 16 to force the rod upwardly and a nut 20 is provided for adjusting said 85 spring. Tubes or guides 21 are secured to the base 1 to provide continuations of the holes in the bed plate through which the rods 16 project. The lower end of each of the tubes 21 is internally screw-threaded 90 to receive the nut 20.

The operation of the press is as follows: Assuming that an insulating tube has been softened and forced upon a mandrel 22 of rectangular shape in cross section, if the 95 tube and mandrel are laid upon the bar 12 of the press, as shown in Fig. 1 of the drawings, it may be permanently formed into the shape which it has assumed by rotating the hand wheel 10 to bring the 100 pressure member 6 into engagement with the surface directly opposite the bar 12. The downward pressure upon the mandrel is transmitted to the bar 12 and from thence through the projections 11 to the rod 105 16, which are consequently forced downwardly below the surface of the bed plate 2 in opposition to the springs 19. Since the adjusting screws 13 prevent the angle plates 110 from separating at their lower edges, a

continued downward pressure on the tube or mandrel will serve to throw the upright portions of the angle plates into engagement with the sides of the tube and thereby compress the tube between their inner faces.

It is obvious that the structural details of the press may be modified to accommodate different kinds of work, and I desire that variations which do not depart from the spirit of my invention shall be included within its scope.

I claim as my invention:

1. A forming press comprising vertically movable bottom and top pressure plates and laterally movable side plates that are interlocked with the bottom plate, and means for moving the top plate to engage the upper edges of the side plates and move them toward each other to compress an interposed object between them.

2. A forming press comprising a base plate, a pair of angle plates having substantially parallel upwardly projecting sides and lateral projections on their adjacent vertical faces, a bottom plate located between the angle plates and resting on said projections, a top plate adjustably supported above the side plates and parallel

to the base plate, adjustable means for limiting the lateral displacement of the angle plates, and yielding means acting upwardly upon the lateral projections of the angle plates.

3. A forming press comprising a base plate having projecting lugs, a pair of angle plates disposed between the lugs on the base plate, adjusting screws threaded through the lugs and engaging the outer edges of the angle plates, a bottom plate disposed between the angle plates and resting on lateral projections thereof, a pressure plate adjustably supported above the angle plates and having its bottom surface parallel to the base plate, and spring-actuated rods which project through the base plate and are adapted to lift the adjacent corners of the angle plates from the base plate when the downward pressure of the top plate is removed.

In testimony whereof, I have hereunto subscribed my name this 8th day of July, 1909.

EMIL HAEFELY.
